UNITED STATES PATENT OFFICE.

JAMES CREIGHTON BLAIR, OF COLUMBUS, OHIO, ASSIGNOR OF TWO-THIRDS
TO OSCAR A. NICKLAUS, OF SAME PLACE, AND ADELBERT D. HOUSTON,
OF LOGAN, OHIO.

FRictional Hinge for Mirrors, &c.

SPECIFICATION forming part of Letters Patent No. 290,829, dated December 25, 1883.

Application filed October 17, 1883. (No model.)

To all whom it may concern:

Be it known that I, JAMES CREIGHTON BLAIR, a citizen of the United States, residing at Columbus, in the county of Franklin and State of Ohio, have invented a new and useful Improvement in Frictional Hinges for Mirrors, &c.; and I do hereby declare that the following is a full, clear, and exact description of the same, reference being had to the accompanying drawings, forming part of this specification, in which—

Figure 1 is a perspective view of my improved frictional hinge applied to a swinging mirror; and Fig. 2 is a front elevation of the same, partly in section.

My invention relates to improvements in frictional hinges for mirrors, &c.; and it consists in the peculiar construction and arrangement of the parts, as hereinafter more fully set forth, and pointed out in the claims.

In the accompanying drawings, I have shown my improved frictional hinge applied to a swinging mirror, (though it may be applied elsewhere,) in which *a* represents one of the stationary uprights or supports to which the mirror is pivoted.

b represents one face of an angular bracket, *o*, provided with holes for the passage of screws *c*, by means of which the bracket *o* is secured to the front face of the upright *a*.

d represents the other face of the bracket *o* at right angles to the face *b*, and provided with an orifice, *n*, for the passage of a split pivot, *h*, hereinafter more fully described.

m represents one of the longitudinal sides of the mirror-frame *m'*.

o' represents an angular bracket composed of the face *b'*, secured by screws *c'* to the longitudinal side *m* of the mirror-frame *m'*.

d' represents the other face of the bracket *o'* at right angles to the face *b'*. The pivot *h* is split centrally at *k*, and the angular faces *b'* *d'* and the split pivot *h* are all made in one piece, or integral with each other.

l represents a washer provided with a central orifice fitting over the pivot *h*.

w represents a wedge, which is driven into the slot *k* in the split pivot *h*, the periphery of the latter being thus forced out tightly against the sides of the orifice *n* in the face *d* of the bracket *o*, and producing friction between the pivot *h* and the sides of the orifice *n*, which thus acts as a stop, and causes the mirror-frame to remain stationary at any desired angle.

Having thus described my invention, what I claim as new, and desire to secure by Letters Patent, is—

1. The frictional hinge herein described, consisting of an angular bracket provided with a split pivot, a second angular bracket provided with an orifice for the passage of the split pivot, and a wedge for expanding the split pivot, substantially as shown and described.

2. The combination, with the mirror-frame *m'* and angular bracket *o'*, secured thereto and provided with the split pivot *h*, of the stationary upright *a*, angular bracket *o*, secured thereto and having the orifice *n*, the angular bracket *o'* and split pivot *h* being all made in one piece, washer *l*, and wedge *w*, substantially as shown and described.

JAMES CREIGHTON BLAIR.
